US00D674276S

(12) **United States Design Patent**
Cohen et al.

(10) **Patent No.:** US D674,276 S
(45) **Date of Patent:** ** Jan. 15, 2013

(54) **CONTAINER SHROUD**

(75) Inventors: **Erica Eden Cohen**, New York, NY (US); **Nathaniel Giraitis**, New York, NY (US); **Jonathan Mandell**, Gurnee, IL (US); **Nicolas Oxley**, New York, NY (US); **Jacob Palmborg**, Brooklyn, NY (US); **Jessi Pervola**, Brooklyn, NY (US); **Richard Whitehall**, New York, NY (US)

(73) Assignee: **S.C. Johnson & Son, Inc.**, Racine, WI (US)

(**) Term: **14 Years**

(21) Appl. No.: **29/430,875**

(22) Filed: **Aug. 30, 2012**

Related U.S. Application Data

(62) Division of application No. 29/379,393, filed on Nov. 18, 2010, now Pat. No. Des. 653,106, and a division of application No. 29/408,160, filed on Dec. 7, 2011, now Pat. No. Des. 669,353.

(51) **LOC (9) Cl.** 09-01

(57) **CLAIM**

The ornamental design for a container shroud, as shown and described.

DESCRIPTION

FIG. 1 is an isometric view of the top, front and right side of the container shroud showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is an isometric view of the top, front and right side of a second embodiment of the container shroud showing our new design;

FIG. 9 is a front elevation view of FIG. 8;

FIG. 10 is a rear elevation view of FIG. 8;

FIG. 11 is a right side elevation view of FIG. 8;

FIG. 12 is a left side elevation view of FIG. 8;

FIG. 13 is a top plan view of FIG. 8; and,

FIG. 14 is a bottom plan view of FIG. 8.

The broken lines are included for the purpose of illustrating portions of the container shroud that form no part of the claimed design.
